UNITED STATES PATENT OFFICE.

THOMAS J. CROOK, OF WICHITA, KANSAS.

OIL-BURNER.

1,070,230.

Specification of Letters Patent. Patented Aug. 12, 1913.

Application filed October 18, 1912. Serial No. 726,515.

To all whom it may concern:

Be it known that I, THOMAS J. CROOK, a citizen of the United States, residing at Wichita, in the county of Sedgwick and State of Kansas, have invented certain new and useful Improvements in Oil-Burners, of which the following is a specification.

My invention relates to improvements in hydro-carbon oil burners and more particularly in the burner forming the subject-matter of my Patent No. 1,042,328, dated October 22, 1912.

In the previous type of burner I have found that when in operation the burning 15 of the flame causes a continuous roaring noise which is exceedingly disagreeable and annoying. This I believe due to the fact that there is in each of the vertical air shafts a column of air, which owing to the difference 20 in temperatures of the air above the column immediately adjacent the burner and the air below the column sets up periodic vibrations which when the burner is in action occur so rapidly as to produce a well defined 25 roaring noise. With a view of overcoming this defect I have experimented along various lines, and have finally discovered that by arranging the air inlets upon opposite 30 marginal edges of the trough of the burner and eliminating the shafts entirely this noise is barely perceptible. I attribute the result to the fact that there is no well defined column of air, and that the air which 35 supplies the burner simply rises through the slots and passes diagonally from opposite sides to the burner, leaving a substantially quiescent body of air therebeneath.

I have also devised a novel arrangement 40 of an overlying retort and a super-heater, whereby the flame issuing from the burner proper will not only heat the oil in the overlying retort but will be deflected to subsequently heat the oil in the super-heater, thereby avoiding any possibility of the 45 condensation of the gases.

To the accomplishment of the stated objects and others coördinate therewith, the preferred embodiment of my invention resides in that construction and arrangement 50 of parts hereinafter described, illustrated in the accompanying drawings, and embraced within the scope of the appended claims.

In said drawings:—Figure 1 is a top plan 55 view of the burner embodying my invention,

and Fig. 2 is an elevation of the same partially in section.

Referring more particularly to the drawings for a detail description of my invention, the numeral 1 designates a trough or base having its opposite longitudinal edges deflected upwardly in planes at right angles to the body of the trough, as at 2. Immediately adjacent each of the flanges is an elongated slot or opening 3 which terminates short of the ends of the trough 1 and is surrounded by vertical walls. The function of these openings will be described later.

As in my previous application for Letters Patent, the oil burner comprises a pair of sections, as 4, and since they are duplicates of each other, a description of one will suffice for an explanation of both. Arranged in parallelism with respect to the trough is an inlet pipe 5 having upon its outer end a needle-valve 6, the opposite or inner end of said pipe being connected to a vertically disposed pipe 7 which carries the section involving an overlying retort, as 8, a super-heater 9 and a burner tube 10. The overlying retort is provided with a rotatably and longitudinally adjustable deflecting disk 11, and the outer end of said retort is connected by means of suitable pipe joints to the super-heater 9 in such manner that the latter will be disposed slightly to one side of the vertical plane or axis of the overlying retort. The super-heater is in turn connected in any suitable manner to the burner tube 10 which is supported by the uprights 12 in vertical alinement with the overlying retort 8, that is to say, the burner tube is deflected rearwardly relative to the super-heater 9 so that it will lie in the same vertical plane with the said overlying retort.

In operation, the needle-valve 6 will be opened to admit the oil, and as it reaches the burner tube 10 it mixes with the air which passes in through the elongated inlets 3. Owing to the fact that the air passing through the said inlets will travel in a substantially diagonal line toward the burner tubes, the body of air below this line of travel will remain practically quiescent, and there will be no column of air to produce rapid reverberations and the consequent roaring sound hereinbefore referred to. When in action the flame rising from the burner tube 10 will strike the overlying re-

retort 8 and thereby initially heat and vaporize the oil, and as the said oil passes through the super-heater it is again subjected to the intense heat of the flame by means of the 5 deflecting-disk 11, so that by the time the oil finally reaches the burner tube and is ready to form an admixture with the air, it will be in a complete state of vaporization. It will also be stated that the vertical 10 flanges 2 serve as a means for deflecting the air issuing through the elongated inlets 3 toward the burner tube 10.

It is desired to reserve the right to effect such modifications and variations of my invention as may come fairly within the scope of the appended claims.

What is claimed is:—

1. In an oil burner, the combination of an open trough, a burner tube, a retort overlying the burner tube, an inlet pipe connected to said retort, said trough having air openings therein arranged in close proximity to its outer edges, and a flange formed adjacent each opening.
2. In an oil burner, the combination of an

open trough, a burner tube, a retort overlying the burner tube, and an inlet pipe connected to said retort, said trough having air openings therein arranged in close proximity to its opposite longitudinal edges.

30

3. In a device of the class described, the combination of a burner tube, a retort overlying said burner tube, a super-heater arranged below and to one side of said retort, and means carried by the retort for deflecting the heat of the burner tube against said super-heater.

35

4. In a device of the class described, the combination of a burner tube, a retort overlying said burner tube, a super-heater arranged below and to one side of said retort, and means rotatably adjustable with respect to said retort for deflecting the heat against said super-heater.

40

In testimony whereof I hereunto affix my signature in presence of two witnesses.

THOMAS J. CROOK.
